UNITED STATES PATENT OFFICE.

ROBERT FELTON, OF NEW YORK, N. Y., ASSIGNOR TO JACOB E. HARTLE, JR., OF NEWARK, NEW JERSEY.

COIN-CONTROLLED VENDING MACHINE.

Application filed October 3, 1923. Serial No. 666,354.

To all whom it may concern:

Be it known that I, ROBERT FELTON, a citizen of the United States, residing at 534 W. 159 St., New York, New York, have invented a new and useful Improvement in a Coin-Controlled Vending Machine; and I do hereby declare the following to be a full, clear, and exact description of the invention, such as will enable others skilled in the art 10 to which it appertains to make and use the same, reference being had to the accompanying drawings, and to characters of reference marked thereon, which form a part of this specification.

This invention relates, generally, to improvements in coin-controlled machines; and the present invention has reference, more particularly, to a novel and simply constructed, as well as an efficiently operating mechanism, assembled in the form of a vending machine, especially adapted for the sale of candy, chewing gum, or other articles of merchandise, with a view of providing a mechanism, in which the depositing of a first coin, will release the mechanism for the delivery of but one piece or article of merchandise, the depositing of a second coin will release the mechanism for the delivery of two pieces or articles of merchandise, and the depositing of a third coin releasing the mechanism for the delivery of three pieces or articles of merchandise, after which, upon depositing other coins, these operations are repeated in sequence, so that further pieces or articles of merchandise may be delivered in the one-two-three order above stated.

The invention, therefore, has for its principal object to provide a coin-controlled apparatus or machine comprising certain controlling mechanisms and parts of the general character hereinafter more fully set forth, and which co-operate with deposited coins to produce the above stated results of delivering pieces or articles of merchandise in the said one-two-three order.

Other objects of the present invention not at this time more particularly enumerated will be clearly understood from the following detailed description of the present invention.

With the various objects of the present invention in view, the said invention consists, primarily, in the novel coin-controlled machine hereinafter set forth; and, the said invention consists, furthermore, in the novel 55 arrangements and combinations of the various devices and parts, as well as in the details of the construction of the said parts, all of which will be more fully described in the following specification, and then finally embodied in the clauses of the claim which are appended to the said specification and which form an essential part of the same.

The invention is clearly illustrated in the accompanying drawings, in which:— 65

Figure 1 is a front face view of a coin-controlled mechanism in the form of a candy or chewing gum vending machine, showing one embodiment of the principles of the present invention; and Figure 2 is a horizontal section of the same, said section being taken on line 2—2 in said Figure 1. Figure 3 is a similar section of the apparatus, said section being taken on line 3—3 in said Figure 1; and Figure 4 is a vertical sectional 70 representation of the apparatus. Figure 5 is another horizontal section of the apparatus, said section being taken on line 5—5 in said Figure 1; and Figure 6 is a plan view 75 of the bottom of the coin-controlled mechanism, looking in the direction of the arrow y in said Figure 1, with the lock-plate usually employed with machines of this character omitted from said view.

Figure 7 is a detail vertical sectional representation of a portion of the casing or frame of the apparatus, showing in elevation a pivoted detent or dog, for actuating a gear, preferably made in the form of a star-wheel; and Figures 8 and 9 are detail 90 vertical sectional representations of the coin-controlled means in the form of a resilient detent or flat spring for primarily locking the movable parts of the mechanism against movement, and secondarily releasing the 95 mechanism for movement of the said parts.

Similar characters of reference are employed in all of the said above described drawings to indicate corresponding parts.

Referring now to the several figures of the 100

drawings, the reference-character 1 indicates a lower base or casing-member, and 2 an upper casing-member, upon which is suitably mounted the usual container 3, made 5 of glass, these several main elements of the apparatus, as will be evident, being of the usual and well-known construction. As shown, the said lower base or casing-member 1 is made with a top 4, and in its lower 10 portion is suitably arranged a lock-plate, as 5, all arranged so as to provide the usual coin-receiving chamber 6. In the top 4 of the said base or casing-member 1 is a suitably formed depression, as 7, leading to 15 a hole or opening 8 in said top 4, which opening communicates with a delivery chute 9, provided with a shelf 10 upon the front of and outside of the side-wall of the base or casing member 1.

20 The above-mentioned upper casing-member 2, which as has been stated is placed upon the lower base or casing-member 1, is detachably secured to the said top 4, by means of any suitable fastening device or means. The said upper casing-member 2 is also made with a suitable top, as 11, which is provided with a suitably shaped opening, as 12. In the front of the side-wall of the said casing-member 2 is the usual coin 25 receiving slot or opening 13, and at a side it is made with a laterally extending lever-receiving slot 14. In addition, the top 11 of the said upper casing-member 2 is provided at a suitable location, upon its under surface, with a downwardly projecting lug or block 15, to which is suitably secured one end-portion of a resilient detent 16, in the form of a flat spring, substantially as shown in Figures 2, 4, 8 and 9 of the drawings. 30 As shown the top 4 of the lower base or casing member 1 is provided with a centrally disposed perforation 17, in which is oscillatorily disposed a stud or post 18, carrying a suitably shaped delivery-element or carriage 19. This element or carriage which is of a cone-shaped configuration, the upper portion of which projects into and through the opening 12 in the top 11, is partially cut away, as at 20, and is provided with a concave delivery or conveying portion 21, in which is formed an opening 22, normally located and movable directly above the previously mentioned groove or depression 7 in the top 4 of the base or casing-member 1. 35 An operating handle or lever 23 extends from the side of said element or carriage 19, into and from the previously mentioned slot 14, and in which slot the said handle or lever is movably disposed. A flange-portion, as 24, is also provided, said flange-portion having a suitably shaped coin-receiving box 25, normally located beneath and in registration with the coin-receiving slot or opening 13 hereinabove mentioned. In close 40 juxtaposition to the said coin-receiving box

25 is an upwardly extending stop-lug or projection 26, with the surface 27 of which the free end-portion 28 of the previously mentioned detent or flat spring 16 is adapted to be brought into arresting engagement to 70 normally prevent the delivery-movement of the said delivery-element or carriage 19. As soon, however, as a coin is deposited into the coin-receiving slot or opening 13, this coin becomes lodged within the coin-receiving box 25, directly in front of the end-portion 28 of the detent or flat spring 16, as indicated in Figure 8 of the drawings. 75

A pull of the operating handle or lever 23, in the direction of the arrow shown in Figure 3 of the drawing, causes the end-portion 28 of the detent or flat spring 16 to ride upon the circumferential edge of the coin, whereby the said detent or flat spring is raised above the path of movement of the stop-lug or projection 26, as indicated in Figure 9, to thereby permit of the proper movement of the delivery-element or carriage 19, as will be clearly evident, this movement carrying the coin with it, by rolling of the coin, directly above a slot or opening 29 in the top 4 of the base or casing member 1.

Referring now more particularly to Figure 4 of the drawings, it will be seen that the top 4 of the base or casing-member 1 is also provided with a properly located perforation, as 30, in which is rotatably disposed a post or stem 31 provided upon its upper end with a head or enlargement 32, and having suitably secured upon its shank, by means of a cotter-pin 33, or otherwise, a carrier-disc or washer 34 and a coil-spring 35. Suitably secured upon the said post or stem 31, between the upper surface of the said top 4 and the head or enlargement 32 is a gear or star-wheel 36, and likewise suitably secured upon the said post or stem 31, between the lower surface of the said top 4 and the upper end-portion of the spring 35 is a suitably-shaped coin-support which consists, essentially of a flat or disk-shaped body-member 37, formed with a pair of oppositely extending wings 38 and 39, and the intermediately disposed cut away or open portions 40 and 41—42, substantially as shown in Figure 6 of the drawings, the wings 38 and 39 being movably disposed beneath the above-mentioned slot or opening 29, so that the delivery-opening of the said slot is adapted to be intermittently opened and closed, the said wings and openings being differently shaped and of such varying lengths, so that the delivery opening of said slot 29 is intermittently opened and will remain open different lengths of time. Rotary movement of the post or stem 31, and consequently of the coin-support, is caused by a pawl or dog 43, pivotally attached, as at 44, in 130

the proper location to the inner wall-portion of the movable delivery-element or carriage 19, as represented in Figure 7 of the drawings, the said dog or pawl being formed 5 with a projection or nosing, as 45, resting in sliding contact upon the upper surface of the top 4 of the main base or casing-member 1, such engagement being produced by the arrangement of a spring-member having 10 a coiled portion 46 encircling the pivot-pin 44, and having one of its end-members 47 secured to the wall-portion of the delivery-element or carriage 19, and its other end-member 48 constantly bearing down upon the upper edge 49 of the said dog or pawl 43, as will be clearly understood from an inspection of said Figure 7 of the drawings. Thus, it will be evident, that during 15 any forward movement of the coin-released delivery element or carriage 19, the projection or nosing 45 of the dog or pawl 43 is moved against one of the teeth of the gear or star-wheel 36, so as to rotate the latter, the spring-member connected with 20 said dog or pawl, as above described, permitting its return, without effecting the position of the gear or star-wheel 36, when a main spring 50 of the usual construction and arrangement, see Figure 3, returns the 25 delivery-element or carriage 19 to its normal initial position.

Having in the foregoing described the general construction of the coin-controlled apparatus, both as to its new features and those which are old in the art, I will now briefly set forth the workings of the device and parts of the same, for the delivery of one, two, and three pieces of merchandise.

Let us suppose that the movable parts of the machine are in the positions indicated in Figures 2, 3, 5 and 6 of the drawings, being locked against movement by the detent or flat spring 16. As soon as a coin is deposited, the detent or flat-spring raised 10 by riding upon the edge of the coin, when the handle or lever 23 is operated, releases the delivery-element or carriage 19 from its locked position, so that the same can be moved. With the rotary forward movement 15 of the element or carriage 19, the coin also moves above the slot 29, and drops down into the main coin-receiving compartment 6. Immediately also an article of merchandise passes down through the opening 8 and passes upon the delivery-shelf 10. During this time, the dog or pawl 43 also activates the gear or star-wheel 36, and by means of the post or stem 31 moves the wing 38 beneath the slot 29, so as to partially close the same, the main spring 50 returning the delivery-element 19 to its normal position, again locked against movement by the detent or flat spring 16. With 15 the next insertion of a coin, the delivery-element or carriage 19 is once more released

for movement, in the manner above stated, and while being operated for the delivery of an article of merchandise, the wing 38 is again moved so as to entirely close the slot 29. The main spring 50 now being permitted to return the delivery-element or carriage 19 to its normal initial position, the coin which was prevented from dropping through the slot 29, also returns with the element or carriage 19, maintaining the 75 raised position of the detent or flat spring 16.

With the next forward movement of the said element or carriage 19, a second piece of merchandise is delivered, the wing 38 moved past the slot 29, bringing the cut away portion or space 40 beneath the slot 29 and allowing the coin to pass down into the compartment 6. Upon its return to its normal initial position, the coin having been removed, the detent or flat spring will again lock the delivery element or carriage against movement, until another coin is inserted for the release of said delivery element or carriage. Upon such depositing of a third coin, the above operations can be repeated, except that owing to the length of the wing 39 and the cut away or open portion 42, the delivery element or carriage 19 can be operated three times in succession, for the delivery of three pieces of merchandise, before the coin finally passes through the slot 29 into the compartment 6.

Of course it will be understood, that by changing the wings, both as to shapes and positions, and by changing the lengths of the cut away or open portions of the coin-support, other delivery combinations of the articles or pieces of merchandise may be made.

I am also aware, that changes may be made in the general arrangements and combinations of the various devices and parts, without departing from the scope of the present invention as set forth in the foregoing specification, and as defined in the clauses of the claims which are appended thereto. Hence, I do not limit my present invention to the exact arrangements and combinations of the several devices and parts as described in the said specification, nor do I confine myself to the exact details of the construction of the said parts, as illustrated in the accompanying drawings.

I claim:

1. In a coin-controlled machine, a casing-member provided with a merchandise-delivery means, and provided also with a top, a delivery-element oscillatorily disposed upon said top, and provided with means for conducting merchandise to the delivery means of said casing-member, means for normally locking said delivery-element against movement, but adapted to be released by engagement of a deposited coin 130

with said locking means, a coin-retaining means connected with said delivery-means, a coin-depositing opening in the top of said casing-member, a post rotatably disposed in the top of said casing-member, a coin-supporting means mounted upon said post for opening and closing said coin-depositing opening, a gear also mounted upon said post, and means carried by said delivery-element for actuating said gear to cause said coin-supporting means to open and close said coin-depositing opening.

2. In a coin-controlled machine, a casing-member provided with a merchandise-delivery means, and provided also with a top, a delivery-element oscillatorily disposed upon said top, and provided with means for conducting merchandise to the delivery means of said casing-member, means for normally locking said delivery-element against movement, but adapted to be released by engagement of a deposited coin with said locking means, a coin-retaining means connected with said delivery-means, a coin-depositing opening in the top of said casing-member, a post rotatably disposed in the top of said casing-member, a coin-supporting means mounted upon said post for opening and closing said coin-depositing opening, a gear also mounted upon said post, and a spring-controlled detent carried by said delivery-element for actuating said gear to cause said coin-supporting means to open and close said coin-depositing opening.

3. In a coin-controlled machine, a casing-member provided with a merchandise-delivery means, and provided also with a top, a delivery-element oscillatorily disposed upon said top, and provided with means for conducting merchandise to the delivery means of said casing-member, a stop-lug carried by said delivery-element, a spring-detent in engagement with said stop-lug for locking said delivery-element against movement, said spring-detent being adapted to be raised out of the path of movement of said stop-lug by engagement with said spring-detent of a deposited coin, a coin-retaining means connected with said delivery-means, a coin-depositing opening in the top of said casing-member, a post rotatably disposed in the top of said casing-member, a coin-supporting means mounted upon said post for opening and closing said coin-depositing opening, a gear also mounted upon said post, and means carried by said delivery-element for actuating said gear to cause said coin-supporting means to open and close said coin-depositing opening.

4. In a coin-controlled machine, a casing-member provided with a merchandise-delivery means, and provided also with a top, a delivery-element oscillatorily disposed upon said top, and provided with means for con-

ducting merchandise to the delivery means of said casing-member, a stop-lug carried by said delivery-element, a spring-detent in engagement with said stop-lug for locking said delivery-element against movement, 70 said spring-detent being adapted to be raised out of the path of movement of said stop-lug by engagement with said spring-detent of a deposited coin, a coin-retaining means connected with said delivery means, a coin-depositing opening in the top of said casing-member, a post rotatably disposed in the top of said casing-member, a coin-supporting means mounted upon said post for opening and closing said coin-depositing opening, a gear also mounted upon said post, and a spring-controlled detent carried by said delivery-element for actuating said gear to cause said coin-supporting means to open and close said coin-depositing opening. 80

5. In a coin-controlled machine, a casing-member provided with a merchandise-delivery means, and provided also with a top, a delivery-element oscillatorily disposed upon said top, and provided with means for conducting merchandise to the delivery means of said casing-member, means for normally locking said delivery-element against movement, but adapted to be released by engagement of a deposited coin with said locking means, a coin-retaining means connected with said delivery-means, a coin-depositing opening in the top of said casing-member, a post rotatably disposed in the top of said casing-member, a coin-supporting disc mounted upon said post, said disc being provided with oppositely extending wings and open portions intermediate of said wings, for opening and closing said coin-depositing opening, a gear also mounted upon said post, and means carried by said delivery-element for actuating said gear to cause said coin-supporting disc to open and close said coin-operating opening. 95

6. In a coin-controlled machine, a casing-member provided with a merchandise-delivery means, and provided also with a top, a delivery-element oscillatorily disposed upon said top, and provided with means for conducting merchandise to the delivery means of said casing-member, means for normally locking said delivery-element against movement, but adapted to be released by engagement of a deposited coin with said locking means, a coin-retaining means connected with said delivery-means, a coin-depositing opening in the top of said casing-member, a post rotatably disposed in the top of said casing-member, a coin-supporting disc mounted upon said post, said disc being provided with oppositely extending wings and open portions intermediate of said wings, for opening and closing said coin-depositing opening, a gear also mounted upon said post, and a spring-controlled detent carried by 120

125

130

5 said delivery-element for actuating said gear to cause said coin-supporting disc to open and close said coin-depositing opening.

6 7. In a coin-controlled machine, a casing-
5 member provided with a merchandise-deliv-
ery means, and provided also with a top, a
delivery-element oscillatorily disposed upon
said top, and provided with means for con-
ducting merchandise to the delivery-means
10 of said casing-member, a stop-lug carried by
said delivery-element, a spring-detent in en-
gagement with said stop-lug for locking said
delivery-element against movement, said
spring-detent being adapted to be raised out
15 of the path of movement of said stop-lug
by engagement with said spring-detent of a
deposited coin, a coin-retaining means con-
nected with said delivery means, a coin-
depositing opening in the top of said casing-
20 member, a post rotatably disposed in the top
of said casing-member, a coin-supporting
disc mounted upon said post, said disc being
provided with oppositely extending wings
and open portions intermediate of said
25 wings, for opening and closing said coin-
depositing opening, a gear also mounted
upon said post, and means carried by said
delivery-element for actuating said gear to
cause said coin-supporting disc to open and
30 close said coin-depositing opening.

35 8. In a coin-controlled machine, a casing-
member provided with a merchandise-deliv-
ery means, and provided also with a top,
a delivery-element oscillatorily disposed up-
on said top, and provided with means for
conducting merchandise to the delivery-
means of said casing-member, a stop-lug
carried by said delivery-element, a spring-
detent in engagement with said stop-lug for
locking said delivery-element against move-
ment, said spring-detent being adapted to
40 be raised out of the path of movement of
said stop-lug by engagement with said
spring-detent of a deposited coin, a coin-
retaining means connected with said deliv-
ery means, a coin-depositing opening
45 in the top of said casing member, a post
rotatably disposed in the top of said
casing-member, a coin-supporting disc
mounted upon said post, said disc being
provided with oppositely extending wings
50 and open portions intermediate of
said wings, for opening and closing said
coin-depositing opening, a gear also mount-
ed upon said post, and a spring-controlled
detent carried by said delivery-element for
55 actuating said gear to cause said coin-sup-
porting disc to open and close said coin-
depositing opening.

60 9. In a coin-controlled machine, a casing-
member provided with a merchandise-deliv-
ery means, and provided also with a top,
a delivery-element oscillatorily disposed
upon said top, and provided with means
65 for conducting merchandise to the delivery-

means of said casing-member, a stop-lug
carried by said delivery-element, a spring-
detent in engagement with said stop-lug for
locking said delivery-element against move-
ment, said spring-detent being adapted to 70
be raised out of the path of movement of
said stop-lug by engagement with said
spring-detent of a deposited coin, a flange-
portion extending from said delivery-ele-
ment, a coin-box forming part of said 75
flange-portion, a coin-depositing opening in
the top of said casing-member, a post ro-
tatably disposed in the top of said casing-
member, a coin-supporting disc mounted
upon said post, said disc being provided 80
with oppositely extending wings and open
portions intermediate of said wings, for
opening and closing said coin-depositing
opening, a gear also mounted upon said post,
and means carried by said delivery-element 85
for actuating said gear to cause said coin-
supporting disc to open and close said coin-
depositing opening.

90 10. In a coin-controlled machine, a cas-
ing-member provided with a merchandise- 90
delivery means, and provided also with a
top, a delivery-element oscillatorily dis-
posed upon said top, and provided with
means for conducting merchandise to the
delivery-means of said casing-member, a 95
stop-lug carried by said delivery-element,
a spring-detent in engagement with said
stop-lug for locking said delivery element
against movement, said spring-detent being
adapted to be raised out of the path of 100
movement of said stop-lug by engagement
with said spring-detent of a deposited coin,
a flange-portion extending from said deliv-
ery-element, a coin-box forming part of
said flange-portion, a coin-depositing open- 105
ing in the top of said casing-member, a post
rotatably disposed in the top of said casing-
member, a coin-supporting disc mounted
upon said post, said disc being provided
with oppositely extending wings and open 110
portions intermediate of said wings, for
opening and closing said coin-depositing
opening, a gear also mounted upon said
post, and a spring-controlled detent carried
by said delivery-element for actuating said 115
gear to cause said coin-supporting disc to
open and close said coin-depositing open-
ing.

120 11. In a coin-controlled machine, a cas-
ing-member provided with a coin-deposit-
ing opening, a delivery-element oscillatorily
mounted with relation to said casing
member, a coin-operated detent for lock-
ing said delivery-element, a coin-support-
ing means disposed beneath said opening,
and a pawl co-operating with said coin-sup-
porting means to permit, primarily, a sin-
gle delivery operation of the delivery-ele-
ment, and, secondarily, a greater number of
delivery operations of the delivery-element. 130

12. In a coin-controlled machine, a casing-member provided with a coin-depositing opening, a delivery-element oscillatorily mounted with relation to said casing member, a coin-operated detent for locking said delivery-element, a coin-supporting disc rotatably supported beneath said opening, said disc having oppositely disposed wings,

and open portions intermediate of said wings, and a pawl co-operating with said disc to permit, primarily, a single delivery operation of the delivery-element, and, secondarily, a greater number of delivery operations of the delivery-element.

ROBERT FELTON.
